SAMUEL G. GOSS, OF CHICAGO, ILLINOIS, AND RALPH C. SEYMOUR, OF LARCHMONT,
NEW YORK, ASSIGNORS TO GOSS PRINTING PRESS COMPANY, A CORPORATION OF
ILLINOIS.

CUTTING AND FOLDING MACHINE.

1,185,088.

Specification of Letters Patent. Patented May 30, 1916.

Original application filed June 10, 1914, Serial No. 844,153. Divided and this application filed August 23,
1915. Serial No. 47,006.

To all whom it may concern:

Be it known that we, SAMUEL G. GOSS, of Chicago, Illinois, and RALPH C. SEYMOUR, of Larchmont, New York, citizens of the United States, have made Improvements in Cutting and Folding Machines, of which the following is a specification.

The invention relates to machines auxiliary to printing presses and like machines, and more particularly to such machines wherein a running web is received and cut and is folded and delivered or is delivered unfolded, and in certain aspects of the invention it relates more particularly to such machines operating with diagonally positioned cutters cutting the running web, but making a square or perpendicular cut in the web.

Other objects and features of the invention will be in part obvious and in part will be set forth hereinafter.

The invention consists in the novel parts, combinations, constructions and improvements herein shown and described.

25 This application is a division of our application Ser. No. 844,153, filed June 10, 1914.

The accompanying drawings, referred to herein and forming a part hereof, illustrate 30 one embodiment of the invention, and together with the description serve to explain the principles thereof.

Of the drawings: Figure 1 is an elevation of a machine constituting an embodiment of the invention; Fig. 2 is a view similar to Fig. 1, but showing the parts in different positions and the machine delivering unfolded sheets; Fig. 3 is a view on an enlarged scale of the central part of Fig. 2, 40 showing the mechanism in a different position and with certain parts omitted; and Fig. 4 is a fragmentary elevation on an enlarged scale showing a different form of web-adjusting or compensating device.

45 In accordance with certain features of the invention, means are provided for making a complete cut or severance of the web, such as is required in the clean-cut edges of magazines and other high class book and 50 like printed work. This is effected by a shearing cut, and for this purpose the cutters are placed at a very slight angle, that is, diagonally or obliquely, to the axis of their carriers, thereby giving a clean, shear-

ing cut to the running web. In order that the shearing cut may be made in the running web by the transversely set blades and at the same time that the cut may be made straight across, that is, perpendicularly to the side edges of the web, means are provided for taking up the web slightly at one side and just sufficiently to compensate for the diagonal gain of the cut across the web as it runs. This compensating take-up is greatest at one edge of the web and gradually diminishes to nothing at the opposite edge of the web.

In accordance with certain features of the invention, the sheets are collected if desired, and in certain aspects of the invention the sheets are delivered either folded or unfolded.

Other features of the invention will be set forth hereinafter in connection with the detailed description.

Referring by way of example, to the embodiment illustrated in the drawing, the web *x* is run in between feed rolls 48 and 49. A pair of traveling carriers are provided for the compensating take up device for the web, and in Figs. 1 and 2 said compensating takeup device is shown of rotary form, and in Fig. 5 said device is shown in reciprocatory form. In Figs. 1 and 2 a cylinder 50 is provided with a compensating depression 51 arranged longitudinally thereof, or parallel to its axis, and arranged to give a momentary transverse diagonal movement to the paper at the cutting point just sufficient to compensate for the set of the cutters and to give a cut perpendicularly or straight across the paper. A coöperating cylinder 53 mounted upon a shaft 54 is provided with a corresponding compensating projection 55, extending longitudinally thereof or parallel to its axis. The projection 55 is greatest at one end of the cylinder and diminishes across the cylinder like the projections 16 in the parent application Ser. No. 844,153. It coöperates with the compensating depression 51 to draw up the sheet most at the edge of the web, and in a decreasing degree across the web just so as to compensate for the set of the cutters.

A cylinder 60 is carried upon a shaft 61 journaled in the machine frame. The cylinder 60 carries cutting blades 62 and 63,

which cutting blades are mounted at a slight angle or obliquely with respect to the axis of the cylinder 60. A cylinder 64 coöperates with the cylinder 60, and has 5 cutting blades 65 and 66, coöperating respectively with cutting blades 62 and 63 on cylinder 60. Suitable guides 67 may be provided to support and direct the web to the cylinders 60 and 64. The cylinder 10 64 is provided with means for retaining the lead or forward end of the web, and so far as concerns many features of the invention, said means may be of any desired form. As shown herein such means comprises 15 impaling pins 68 and 69 mounted and operating in a well-known manner.

Means are provided by the invention for delivering the sheets unfolded, or for delivering the sheets singly folded, or for delivering the sheets collected and folded, as may be desired. In the embodied form of such means, the folding devices comprise reciprocating folding blades 80 mounted in the cylinder 64. Said folding blades have a pin 20 and slot connection with the slots 81 in lever arms 82 at each end of the folding blades 80. The arms 82 are fixed, respectively, to rock shafts 83 carried by the cylinder 64. Spring 84 is connected to the arms 82. Fixed 25 to the shafts 83 are actuating arms 85, provided with cam rolls 86. Said cam rolls coöperate, respectively with suitable cams 87 upon the machine frame, to project the folding blades 80 at the proper time to fold 30 the sheets into the corresponding folding jaws.

Coöperating with the cylinder 64 to fold the sheets, is a cylinder 90 carried by shaft 91 journaled in the machine frame. The 40 cylinder 90 is provided with sets of folding jaws 92 of any suitable form. Folding jaws 92 are carried by rock shafts 93, said shafts 93 being mounted in the cylinder 90. Fixed to the respective rock shafts 93 is an actuating arm 94, carrying a cam roller 95, and acted upon by a spring 96. A cam 97 fixed upon the machine frame coöperates with the cam roller 95 to open and close the folding jaws to take the fold, and to deliver the 50 sheet.

The form of delivery devices shown comprises an intermittent carrier or conveyer belt 98 carried upon rollers 99 and driven in a suitable manner (not shown). The 55 form of flat delivery embodied in said Figs. 2 and 3 comprises tapes 110 and 111 running over rollers 112 and 113, and constituting a sheet pathway conducting away the sheets from the cylinders 60 and 64. 60 Means are provided for directing the lead edge of the successive sheets between the tapes 110 and 111, to be conveyed away thereby. As embodied, a series of fingers 114 are carried in recesses in the cylinder 64. Said fingers 114 are mounted on a rock

shaft 115, said shaft being mounted in the cylinder 64. Fixed to the rock shaft 115 is an actuating arm 116 provided with a cam roller 117. The cam roller 117 coöperates with a cam 118 on the machine frame. 70

The manner of operation of the mechanism shown and described is substantially as follows: The web *x* runs in between the feed rollers 48 and 49. When it is desired to cut the sheets and deliver them flat, the cam 118 is moved into operative relation with the cam roller 117, and the guiding and supporting fingers 114 are raised as shown in full lines, and then pass through the positions shown in dotted lines in Fig. 3, thus lifting the lead end of the web from cylinder 64 and feeding it into the tape pathway 110 and 111. The cutters 63 and 66 or the cutters 62 and 65 sever the sheet, which is then conveyed away. When it is desired to cut and fold, the grippers or impaling pins 68 carry the lead end of the web about the cylinder 64, and the folding blades 80 fold the center of the sheet into the folding jaws 92. The sheet is then released by the grippers or impaling pins 68 to the cylinder 90 and by said cylinder is delivered to the conveyer 98. When it is desired to collect, the folding blades and folding jaws 80 and 92, respectively, and the grippers or impaling pins 68 are arranged to operate intermittently and periodically so as to take upon the cylinder 64 two or more sheets in superimposition and then fold them off together in the manner already described for a single sheet. 90

From all the foregoing it will be understood that a machine has been provided embodying the objects and advantages herein set forth, together with other objects and advantages. It will be understood also that changes may be made from the mechanisms shown and described within the scope of the accompanying claims, without departing from the principles of the invention and 105 without sacrificing its chief advantages.

What we claim as our invention and desire to secure by Letters Patent is:—

1. A folding and cutting machine including in combination a web supply, a cylinder 115 having an obliquely arranged cutter and having a folding device, a cylinder carrying a coöperating oblique cutter, a cylinder carrying coöperating folding means and compensating means for causing said cutters 120 to make a perpendicular cut in the web.

2. A folding and cutting machine including in combination oblique cutters, compensating means for producing a perpendicular cut therefrom, folding mechanism, 125 and devices whereby the cut sheets may be delivered folded or unfolded.

3. A folding and cutting machine including in combination a web supply, oblique cutters, compensating means for producing 130

a perpendicular cut therefrom, folding mechanism and devices whereby the cut sheets may be delivered folded or unfolded.

4. A folding and cutting machine including in combination rotating oblique cutters, compensating means for producing a perpendicular cut therefrom, folding mechanism and devices whereby the cut sheets may be delivered folded or unfolded.

10 5. A folding and cutting machine including in combination a source of web supply, rotating oblique cutters, compensating means for producing a perpendicular cut therefrom, folding mechanism and devices whereby the cut sheets may be delivered folded or unfolded.

20 6. A folding and cutting machine including in combination oblique cutters, rotating compensating means for producing a perpendicular cut therefrom, folding mechanism and devices whereby the cut sheets may be delivered folded or unfolded.

25 7. A folding and cutting machine including in combination rotating oblique cutters, rotating compensating means for producing a perpendicular cut therefrom, folding mechanism and devices whereby the cut sheets may be delivered folded or unfolded.

30 8. A folding and cutting machine including in combination a cylinder having an oblique cutter, an oblique cutter coöperating therewith, compensating devices for producing a perpendicular cut from said cutters, devices carried on said cylinder for trans-

ferring the sheets therefrom either flat or folded, and folding mechanism for folding the sheets when desired.

9. A folding and cutting machine including in combination a web supply, a cylinder having an oblique cutter, an oblique cutter coöperating therewith, compensating devices for producing a perpendicular cut from said cutters, devices carried on said cylinder for transferring the sheets therefrom either flat or folded and folding mechanism for folding the sheets when desired.

10. A folding and cutting machine including in combination a cylinder having an oblique cutter, an oblique cutter coöperating therewith, compensating devices for producing a perpendicular cut from said cutters, devices carried on said cylinder for transferring the sheets therefrom either flat or folded and devices for receiving the sheets from said cylinder, and folding mechanism for folding the sheets when desired.

In testimony whereof we have signed our names to this specification, in the presence of two subscribing witnesses.
